DESIGN FOR A HEATER

Don F. Jones and Mervin F. Cotes, Lansing,
Mich., assignors to Motor Wheel Corporation,
Lansing, Mich., a corporation of Michigan

Application February 10, 1936, Serial No. 61,076

Term of patent 7 years

To all whom it may concern:

Be it known that we, Don F. Jones and Mervin F. Cotes, citizens of the United States, residing at Lansing, in the county of Ingham and State of Michigan, have invented a new, original, and ornamental Design for a Heater, of which the following is a specification, reference being had to the accompanying drawing, forming a part thereof.

In the drawing, the figure is a perspective view

of a heater showing our new design. The heater is of cylindrical formation and without ornamentation other than as shown. In other words, the rear of the heater is plain.

We claim:

The ornamental design for a heater as shown and described.

MERVIN F. COTES.
DON F. JONES.
